Inventor:

William S. Hamm,

By *Purcell, Great & Warner* Atty.

Wilson, the qualifications of which are sufficiently well known, will be invited to offer his services. The present Foreign Service is to be placed under his command, and may be soon strengthened by the addition of an additional 1500 men, 1500 additional men being required to maintain the half-million men now in the service.

UNITED STATES PATENT OFFICE

1,986,773

CURTAIN CONSTRUCTION

**William S. Hamm, Elkhart, Ind., assignor to The
Adlake Company, Chicago, Ill., a corporation of
Illinois**

Application October 14, 1932, Serial No. 637,799

1 Claim. (Cl. 156—26).

This invention has to do with window curtain assemblies of the type commonly used in automobiles, in which the curtain is mounted on a spring wound roller and cords are employed at the sides of the curtain in sliding engagement with a batten in a hem in the bottom of the curtain for guiding the latter.

The primary object of the invention is to provide, in an assembly of the type described, 10 novel cushioning means for bringing the curtain to a stop quietly without shock or injury when the curtain is released and allowed to roll all the way up under the action of the spring in the roller.

15 While the foregoing statement is indicative in a general way of the nature of the invention, other more specific objects and advantages will be apparent to those skilled in the art upon a full understanding of the construction, arrangement and operation of the cushioning means.

Three slightly different embodiments of the invention are presented herein by way of exemplification, but it will of course be appreciated that the invention is capable of being embodied in still other structurally modified forms coming equally within the scope of the appended claim.

In the accompanying drawing:

Fig. 1 is a front view of a window curtain assembly equipped with the improvement of the invention:

Fig. 2 is a partially sectioned front view of one of the ends of the batten:

Fig. 3 is an end view of one of the supporting brackets:

Fig. 4 is a front view of the bracket shown in Fig. 3;

Fig. 5 is a horizontal section, taken on the line 5-5 of Fig. 2;

Fig. 6 is a partially sectioned fragmentary front view of an assembly which embodies a

Fig. 7 is an end view of a supporting bracket in which the invention is embodied in a further modified form of the invention;

45 Fig. 8 is a front view of the bracket shown in Fig. 7.

The form of the invention which is shown in Figs. 1 to 5 inclusive will first be described. In

50 Figs. 1 to 5 inclusive will first be described. In those views a window curtain assembly is illustrated which includes a soft flexible curtain 10, a spring wound roller 11 on which the curtain is mounted, brackets 12 at the ends of the roller for rotatably supporting the latter, a batten 13 in a hem 14 in the bottom of the curtain, and 55 guide cords 15 at the sides of the curtain which

The batten 13 is preferably made of metal, and the ends of the same are provided with flat horizontal eyes 16 in which small rubber tubes 17 are disposed in vertical positions. The tubes 17 project short distances above and below the eyes 16 and are grooved at 18 in order to interlock vertically with the eyes. The guide cords 15 are threaded through the rubber tubes 17, 10 in loosely sliding engagement with the latter, and the lower ends of the cords are attached by means of tacks or screws 19 to the framework of the window adjacent the lower corners of the latter. The upper ends of the cords 15 are threaded through apertured ears 20 which project horizontally from the lower portions of the brackets 12 into positions directly above the tubes 17 in the ends of the batten. Above the ears 20 the cords are threaded through small 20 holes 21 in the brackets behind the heads of the latter and are securely knotted at 22 against the brackets to prevent withdrawal. The cords of course might be knotted just above the ears 20, but a neater appearance is obtained by extending the ends up back of the roller in the manner shown.

When the curtain 10 is released in order to permit the same to move up into its fully raised position under the action of the spring in the roller 11, the cords 15 will serve to guide the upwardly projecting rubber tubes 17 on the ends of the batten 13 into centered abutment with the ears 20 on the brackets 12, with the result that the batten and curtain will come to rest quietly in a horizontal position without any appreciable jar and without any danger of the edge portions of the curtain being mulched between any sharp contacting parts of the batten and brackets. The rubber tubes 17 not only cushion the batten and curtain in bringing the same to rest but also are preferably so arranged as to prevent any metal-to-metal contact at the time of impact. The members 17 are preferably made of rubber, in the form of eyelets, but they may be made of other materials, in the same or different forms.

In the modification which is shown in Fig. 6, the ends 23 of the batten 24 are flattened out horizontally and provided with apertures 25. The apertures 25 are preferably made only large enough to accommodate the vertically extending guide cords 26. In this form of the invention, the desired cushioning effect is again obtained by the use of rubber eyelets 27 which are se-

cured within suitably apertured ears 28 which project horizontally from the lower portions of the brackets 29. The guide cords 26 extend upwardly through the eyelets 27, and the upper 5 ends of the cords are secured to other portions of the brackets in the same manner as in the first described embodiment of the invention. When the curtain 30 is released and allowed to run up under the spring wound action of the 10 roller, the cords 26 at the sides of the curtain will guide the flattened ends of the batten 24 into centered abutment with the lower ends of the rubber tubes 27, and the curtain and batten will be brought to rest quietly and without any 15 wear or tear.

The modification which is shown in Figs. 7 and 8 resembles that which is shown in Figs. 1 to 5 inclusive in that the shock-absorbing elements 31 are carried by the ends of the batten instead of by the brackets. In this particular embodiment of the invention the brackets are shown as being made for the most part of wire. The leg and attaching portions of the brackets are made from single pieces 32 of 25 wire, while the heads of the brackets consist of sheet metal stampings 33 which are marginally flanged about the looped central portions 34 of the wires. The eyes 35 in the ends of the batten, in which the cushioning elements 31 30 are mounted and through which the guide cords 36 are threaded, are preferably of slightly smaller diameter than the cushioning elements, whereby to cause the edges of the latter to project a little beyond the edges of the eyelets 35 and thus prevent any metal-to-metal contact between the eyes and the brackets. The cushioning elements 31, instead of moving upwardly into abutment with horizontally disposed stops on the brackets, may merely engage with the lower portions of the legs and heads of the 40 brackets, the laterally projecting character of

the cushioning elements preventing any metal-to-metal contact between the parts. The upper ends of the guide cords 36 are passed through apertured ears 37 on the rear portions of the caps 33 and are knotted behind such portions 5 in concealed positions.

The cushioning elements are shown as being of tubular formation but other formations are of course contemplated. The cushioning elements may be manufactured at very little cost 10 and may be easily inserted or replaced by merely collapsing them and then passing them through the apertures in the batten or brackets while in a collapsed condition. Upon being released in their proper positions, the elements will immediately reassume their original shapes and move into vertically interlocked association with the batten or brackets. After the guide cords have been threaded through the cushioning 15 elements, the latter will of course be prevented from collapsing. 20

I claim:

In a window curtain assembly, having a spring wound roller, a curtain on the roller, brackets at the ends of the roller, a batten having an aperture in each end thereof, said batten being positioned in a hem at the bottom of the curtain, and cords at the sides of the curtain threaded through said apertures in the ends of the batten for free sliding movement with respect to the same, means for causing the curtain to come to rest, quietly in its rolled up position upon being released, said means consisting of rubber bushings which fit loosely about the cords within the apertures in the ends of the batten and project upwardly therefrom for impingement with vertically aligned portions of the brackets, and said cords being threaded through said bushings. 30

WILLIAM S. HAMM. 40
